(57) **CLAIM**

The ornamental design for the orthopedic safety boot as shown and described.

DESCRIPTION

FIG. 1 is a top perspective view of the orthopedic safety boot;

FIG. 2 is a bottom perspective view thereof;

FIG. 3 is a front view thereof;

FIG. 4 is a side view thereof;

FIG. 5 is a top view thereof;

FIG. 6 is a bottom view thereof;

FIG. 7 is a top perspective view of the orthopedic safety boot of FIG. 1, shown in condition of use for clarity of disclosure; and,

FIG. 8 is a side view thereof.

The broken lines illustrates environmental subject matter which form no part of the claimed design.

1 Claim, 8 Drawing Sheets
